GAS CASE-HARDENING FURNACE

Leon Saives, Billancourt, France, assignor to
Louis Renault, Billancourt, FranceApplication September 9, 1936, Serial No. 100,054
In France July 16, 1936

1 Claim. (Cl. 266—5)

The present invention relates to improvements in gas case-hardening furnaces.

An object of the invention resides in the provision of means for ensuring rapid diffusion of the fresh gases entering the furnace by whirling the gases into the muffle chamber of the furnace.

Another object of the invention is to provide means on the outside of the furnace which will force fresh gases into the muffle chamber in such a manner that the added gases are more thoroughly mixed with the gases already in the furnace to thus obtain substantially the same temperature and chemical composition throughout the furnace.

15 In order to allow of ready comprehension of the invention, it will be more particularly described with reference to the attached drawing, in which:

The single figure is a transverse section of a 20 muffle furnace furnished with a device for the diffusion of fresh gas.

The improvement relates to the gas inlets and has for effect the rendering certain of the diffusion of the fresh gas by energetic stirring 25 inside the furnace.

This device assures uniform distribution of the chemical composition and of the temperature.

The characteristic of this device resides in the fact that no stirring fan is introduced into the 30 furnace because the construction of such fans is complicated and the working defective, especially at high temperatures, when case-hardening with carbon.

The drawing shows one example of construction.

The cementing gas arrives at 1 into the chamber 2 which provides a housing for a centrifugal fan 3. The fan has a radial projecting action but there is no radial outlet in the chamber 2 40 and the gas can escape only by way of an axial cone 4 terminated by a connecting piece 4¹ opening at a suitable place into the cementing muffle 5. The gas by action of the fan receives a gyroscopic movement but the speed of motion in the 45 direction of the axis of the fan, is not substantially increased. The shaft 6 of the fan which leaves the chamber 2 through a stuffing box 7 is guided in bearings 8 and 9 and driven by a motor 10 by means of a flexible coupling 10. The 50 cementing muffle 5 is housed in the inside of a furnace represented by its refractory lining 12 and insulating lining 13. The muffle rests on rollers 14 allowing its free expansion. The objects to be case-hardened 15 are put on tables 55 15 which are pushed end to end into the muffle 5.

The method of working is as follows: in the first place the flow of cementing gas in 1 is adjusted to suit requirements. By reason of the rotation of the fan 3 the gas is animated by an intense gyroscopic movement. By application of the theorem of kinetic moment, and since the gyrating gas is confined in the cone 4, the moment of the quantity of movement is constant, and the speed of rotation of a molecule of gas is inversely proportional to its distance from the axis of the cone.

As the gas descends in the cone 4 its speed of rotation increases and becomes very great in the connecting piece 4¹.

Upon entering the muffle 5, the gas gives rise to a vortex with vertical axis which fills the whole section of the muffle. Moreover, in the axis of this cyclone there is produced a vacuum which sucks up the gas from below to above along the axis while the gas whirls in descending near the walls of the muffle.

This energetic stirring assured the homogeneity of distribution of the temperature and of the chemical composition, even in the vicinity of the gas inlet connection.

There is thus avoided the dissociation or energetic cracking to which the new cementing gas would give rise if it were not first diluted in a great mass of gas already in equilibrium with the temperature.

It thus results that the cementing is much more constant and more regular.

Owing to the arrangement of the stirring fan 3 which is outside of the furnace and remains cool, its construction is easy and its working certain. The thermal efficiency is excellent.

Finally, the cementing is very regular and retains all its efficacy in the concave parts and bores of the objects treated.

I claim:

In a gas case-hardening furnace, a muffle chamber, means for introducing cementing gas into the muffle chamber comprising a centrifugal fan having a gas supply communicating therewith, means for rotating the fan, a housing for the fan having a downwardly extending cone-shaped portion with the apex thereof communicating with said muffle chamber, whereby the gas is moved into the chamber by whirling the molecules of the same in the cone-shaped housing and in such a revolving condition is mixed with the gases in the muffle chamber.
